UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

FIBER-CASE RAILWAY-TORPEDO.

1,182,537.

Specification of Letters Patent.

Patented May 9, 1916.

Application filed May 22, 1915. Serial No. 29,851.

To all whom it may concern:

Be it known that I, FRANK DUTCHER, a citizen of the United States, residing at Versailles, in the county of Allegheny and State of Pennsylvania, have invented certain new and useful Improvements in Fiber-Case Railway-Torpedoes, of which the following is a specification, reference being had therein to the accompanying drawing.

10 My invention relates to improvements in fiber case railway torpedoes.

The object of my invention is to provide an open ended case in which the explosive tablet is placed and a sealing composition 15 forming the top of the case.

Another object of my invention is to provide a torpedo of this character in which the explosive tablet is more tightly sealed within the case and having certain details of structure and operation hereinafter more fully set forth.

In the accompanying drawings—Figure 1 is a perspective view of my improved torpedo showing the rail-attaching clip applied. Fig. 2 is a transverse sectional view. Fig. 3 is a vertical transverse sectional view of a modified form taken at right angles to Fig. 2. Fig. 4 is a bottom perspective view of Fig. 1.

20 Referring now to the drawings, 1 represents the open ended case of my improved torpedo, which is preferably of a saucer shape and having its upper end open, as fully shown in Fig. 2 of the drawings. The bottom 2 of the case 1, has slits 3 and 4 adjacent its sides and the material of the bottom pressed downwardly, as indicated at 5, and forming a space for the passage of the rail-attaching clip 6, as fully shown in Figs. 2 and 4 of the drawing.

Surrounding the vertically disposed walls 7 of the case 1, is a band 8, which has its upper end extending a slight distance above the vertical walls 7 of the case. This band prevents the expanding of the vertical wall 7 of the case 1. The case 1 is preferably pressed from a sheet of fiber or like material and this band positively insures against the expanding of the vertical wall 7 of the case. A cementing or sealing composition 9 is placed in the lower end of the case 1, and the explosive tablet 10 is placed therein and forced downward, thus forcing the cementing composition downwardly and filling the space formed by the depressed portion 5.

The sealing composition will also force its way around the oblique walls 11 of the explosive tablet 10. A sealing composition 10', similar to that placed in the bottom of the case, is placed upon the upper face of the explosive tablet and is forced downwardly around the oblique walls 11 of the tablet 10. A sufficient amount of sealing composition is placed within the case to bring it flush with the upper edge of the ring 8, and by this arrangement it will be seen that the sealing composition rests upon the upper edge of the vertical wall 7 of the case 1 and forms a tight joint so that it is impossible for any moisture to seep down around the inner face of the vertical wall 7. By this arrangement it will be seen that a smooth upper face torpedo is formed which does away with the usual double case container and at the same time absolutely seals the explosive tablet against moisture.

In the modification shown in Fig. 3, I have shown a slightly modified form. In this modification, the cement is placed in the bottom of the container the same as in Fig. 2, but the disk 12 is first placed in the container on the cement and the cement is forced upwardly around the edge and securely locks the disk in the bottom of the container. The explosive tablet 10 is then placed in the container on the upper faces of the disk 12 and the container above the explosive mixture is then filled in with the cement the same as that shown in Fig. 2. In each instance, the entire torpedo is dipped into the water-proof composition to absolutely insure a water-tight case. The proper application of the invention is the placing of an explosive tablet of composition within a case and filling the space around the explosive tablet with a sealing composition so that the sealing composition holds the explosive tablet within the case and also forms the top of the case which is shown in both the preferred form and the modification. While I have shown this specific arrangement of the container, it will be understood that this could be changed without departing from my invention.

Having thus described my invention, what I claim and desire to secure by Letters Patent is:

1. A railway torpedo comprising a case having an open face, an explosive tablet within the case, and a sealing composition

filling the case around and above the explosive tablet and forming the top of the case.

2. A railway torpedo comprising a case having an open face, a band around the case and extending a slight distance above the top of the case, an explosive tablet within the case and a sealing composition filling the case above the tablet flush with the 10 upper edge of the band and forming the top of the case.

3. A railway torpedo comprising a case having a central depressed portion forming a clip-attaching means, a sealing composition within the bottom of the case and filling the depressed portion of the case, an explosive tablet within the case and a sealing composition filling the case above and around the explosive mixture and forming 20 the top of the case.

4. A railway torpedo comprising a case having a central depressed portion, a rail-attaching clip passing through the depressed portion, a sealing composition with- 25 in the bottom of the case and filling the depressed portion above the clip, an explosive mixture tablet within the case, and a sealing composition filling the space around and above the explosive tablet flush with the 30 upper edge of the case and forming the top of the case.

5. A railway torpedo comprising a case having an open face having a depressed portion in its bottom, a rail attaching clip 35 passing through the depressed portion, a sealing composition within the bottom of the case, a band surrounding the vertical walls of the case, and a sealing composition filling the case and extending over the upper edge thereof and flush with the upper edge of the band and forming the top of the case.

6. A railway torpedo comprising a case having an open face, a disk cemented within 45 the lower end of the case, an explosive tablet within the case and a sealing composition filling the case around and above the explosive tablet and forming the top of the case.

7. A railway torpedo comprising a case, having a central depressed portion, a rail-attaching strip passing through said depressed portion, a disk cemented within the 55 bottom of the case, an explosive tablet within the case and resting upon the disk and a sealing composition filling the case around and above the explosive tablet and forming the top of the case.

8. A railway torpedo comprising a case 60 having an open face having a depressed portion in its bottom, a disk cemented in the bottom of the case, a band surrounding the vertical walls of the case and extending above the upper edge thereof, an explosive 65 tablet within the case and resting upon the disk and a sealing composition filling the case around and above the explosive tablet flush with the upper end of the band.

9. A railway torpedo comprising a case 70 having an open face having a depressed portion in its bottom, a disk cemented in the bottom of the case, a band surrounding the vertical walls of the case and extending above the upper edge thereof, an explosive 75 tablet within the case and resting upon the disk, a sealing composition filling the case around and above the explosive tablet flush with the upper end of the band, and a water- proof composition entirely covering the 80 case.

10. A railway torpedo comprising a case having an open face having a depressed portion in its bottom, a rail-attaching clip passing through the depressed portion, a sealing 85 composition within the bottom of the case, a band surrounding the vertical walls of the case and extending above the upper edge thereof, an explosive tablet within the case, a sealing composition filling the case and ex- 90 tending over the upper edge thereof and flush with the upper edge of the band and forming the top of the case, and a water- proof composition entirely covering the 95 case.

11. An improved torpedo of the character described, comprising a flat case having a bottom and an open top, an explosive tablet within the case and a cement composition within and entirely closing the open top 100 of the case and forming a cement top therefor and serving to hold the explosive therein.

12. An improved torpedo of the character described, comprising a flat case having a bottom and open top, a tablet explosive 105 within the flat case, the open top of the case projecting beyond the explosive and a cement composition within and completely filling the open top of the case and forming a cement top therefor and serving to in- 110 close and hold the explosive tablet therein.

In testimony whereof I hereunto affix my signature in the presence of two witnesses.

FRANK DUTCHER.
